TREATMENT OF WELLS

Paul G. Shelley, Midland, Mich., assignor to The Dow Chemical Company, Midland, Mich., a corporation of Michigan

No Drawing. Application April 23, 1940,
Serial No. 331,207

5 Claims. (Cl. 166—21)

The invention relates to the treatment of oil and gas wells with a fluid reagent to facilitate the production therefrom. It more particularly concerns an improved method of removing clogging deposits of paraffin, wax, and the like from the small pores and flow channels of the producing formation of such wells.

It is well known that the porous formation constituting the oil and gas bearing stratum gradually becomes clogged with waxy asphaltic deposits commonly called paraffin as the well is produced. Heretofore it has been proposed to remove such clogging deposits from the pores and interstices of the producing formation by introducing into the well solvents of the type which are capable of at least partially dissolving the paraffin and like matter. Such solvents may be gasoline, petroleum naphtha, carbon tetrachloride, tetrachlorethylene and the like. In using such solvents, it is usually the practice to introduce the solvent into the well and force it into the surrounding formation where it is to act. However, the use of such solvents in the above manner has some serious disadvantages. For example, the solvent has a relatively high solvent action on the paraffin as it enters the formation, and soon becomes saturated with dissolved constituents of the paraffin. Thereafter these solvents, which are readily miscible with the oil present in the formation, may and often do become diluted therewith and lose some of their solvent action as they are allowed to remain in contact with the paraffin deposit, so that a portion of the dissolved paraffin reprecipitates, with the result that the pores of the formation may again be plugged by the redeposited paraffin. This disadvantage is especially pronounced when an attempt is made to force the paraffin solvent deeply into the formation, due to the fact that there is an opportunity for the solvent to become supersaturated as it is caused to contact additional quantities of the paraffin, and at the same time there is more chance that reprecipitation will occur, due to the fact that the solvent comes in contact with a larger volume of oil or other fluid acting to dilute the solvent.

It is, therefore, an object of the invention to provide a method of treating wells with a paraffin solvent whereby the action of the solvent on the paraffin may be substantially delayed or retarded, so that the solvent will exert substantially no solvent action during the time it is being forced into the formation.

Another object of the invention is to provide

5 a method of treating wells with a paraffin solvent, whereby saturation of the solvent can be substantially prevented during the period when it is being introduced into the formation.

10 Other objects and advantages will be apparent as the description of the invention proceeds.

Briefly the method of the invention comprises introducing into the earth or rock formation surrounding the well bore a paraffin solvent that 15 has been cooled just prior to its being forced into the formation to such a temperature that it will not substantially attack or dissolve paraffin or constituents thereof. Such solvent can be forced deeply into the formation before it becomes warmed by contact with the formation to the extent that it will exert a solvent action up on the waxy or asphaltic constituents of the paraffin so as to become saturated with such constituents. Further, the solvent becomes diluted with the well fluids before it can act to dissolve any considerable quantity of paraffin and thus its solvent power becomes substantially stable prior to becoming saturated with paraffin. After the solvent has been forced into the formation to the desired depth, it is held in place by application of pressure, if necessary, until sufficient time has elapsed to allow the solvent to become warmed. The solvent becomes warm as it remains in contact with the earth formation, since the temperature of the producing formations of oil and gas wells is usually between 100°—150° F. As the solvent becomes warmed, it attacks paraffin deposited in the formation causing the paraffin to disintegrate. The 20 mixture then readily flows into the well bore through the flow channels which have been greatly enlarged by the action of the solvent. Since the cooled solvent does not immediately act to dissolve the constituents of the paraffin, saturation of the solvent first entering the formation is substantially prevented, and thus redeposition of the paraffin from the solvent is 25 largely susceptible of control.

The temperature to which the solvent is to be 30 cooled just prior to its introduction into the formation may vary, depending upon the depth the solvent is to be forced into the formation, and the temperature of the formation to be treated. I have found that generally satisfactory results are obtainable by cooling the solvent to a temperature from about 5 to —20° C. It has been found preferable in practice to cool the solvent in the well bore just prior to its introduction into the formation, for if an attempt is made to cool the solvent at the

earth's surface and thereafter introduce it into the well, the solvent becomes warmed by the heating action of the well equipment and fluids contained in the well before it can reach the bottom of the well bore. On the other hand, cooling the solvent in the well bore just prior to its introduction into the formation results in the solvent entering the formation having the lowest solvent action possible during the time it is being forced to the desired location. Cooling of the solvent in the well bore is accomplished by placing a quantity of ice, dry ice, or the like, depending upon the temperature desired, in the well bore, preferably after the well fluids have been removed therefrom, as by forcing them back into the formation. The solvent is then introduced into the well bore and allowed to come in contact with the cooling agent.

In carrying out the method of the invention in a well, any liquid standing in the well bore is first preferably removed therefrom, as by forcing it back into the formation, or by bailing the well to remove such liquids. A quantity of the cooling medium is then placed in the well bore and the solvent introduced into the well through the tubing, if such be present. The solvent may be allowed to remain in contact with the cooling agent for a length of time calculated to produce the desired degree of cooling. After the desired amount of solvent has been introduced into the well, it may be displaced therefrom into the formation by applying a hydrostatic pressure thereon, as by pumping a fluid such as oil or water into the well on top of the solvent.

The amount of the solvent generally required to bring about the desired effect may vary, depending upon the depth the solvent is to be forced into the formation and the extent of the formation to be treated. I have found that generally satisfactory results are obtained by employing 50-250 gallons or more of the desired solvent.

The solvent is held in place until sufficient time has elapsed for it to become warmed, or until it reaches the temperature of the formation and acts upon the paraffin deposited therein. From 1-5 hours or more are usually necessary to warm the solvent to a point where it acts upon the paraffin satisfactorily, depending, however, upon the temperature of the surrounding formation and the temperature of the solvent when introduced. After a sufficient time has elapsed to permit the solvent to function in the desired manner, the solvent and dissolved constituents are allowed to return to the well bore and are removed therefrom, as by pumping the well or by a bailing operation.

If desired, the introduction of fresh solvent and withdrawal of spent solvent may be repeated one or more times to insure a more thorough cleaning of the flow channels.

Among the advantages of the invention are that conventional paraffin solvents may be employed to remove clogging deposits of paraffin from the flow channels of the formation without

danger of the solvent entering the formation becoming saturated with paraffin while in an undiluted state so that the paraffin is later precipitated out of solution, plugging the pore channels of the formation; and that the paraffin deposited deeply in the pores and interstices of the formation may be readily reached and removed by the solvent, because the solvent action of the paraffin has been retarded so that when it contacts the paraffin deposited more deeply it still functions as a highly effective solvent.

This application is a continuation-in-part of my co-pending application Serial No. 215,228, filed June 22, 1938.

15 Other modes of applying the principle of my invention may be employed instead of those explained, change being made as regards the method herein disclosed, provided the step or steps stated by any of the following claims or 20 the equivalent of such stated step or steps be employed.

I therefore particularly point out and distinctly claim as my invention:

1. In a method of treating a well to remove 25 paraffin and the like, the steps which include introducing into the well bore a cooling agent, introducing a quantity of paraffin solvent into the well bore whereby the paraffin solvent is cooled by contact with said cooling agent, and 30 thereafter forcing said cooled solvent into the surrounding formation.

2. In a method of treating a well to remove paraffin and the like, the steps which consist in introducing into the well bore a solid cooling 35 agent, introducing into the well bore a quantity of paraffin solvent whereby the paraffin solvent is cooled by contact with said cooling agent, and then forcing the cooled paraffin solvent into the surrounding formation.

3. In a method of treating a well to remove 40 paraffin and the like, the steps which consist in introducing ice into the well bore, introducing into the well bore a quantity of paraffin solvent whereby the paraffin solvent is cooled by contact 45 with the ice, and then forcing the cooled paraffin solvent into the surrounding formation.

4. In a method of treating a well to remove 50 paraffin and the like, the steps which consist in introducing a quantity of solid carbon dioxide into the well bore, introducing into the well bore a quantity of paraffin solvent whereby the paraffin solvent is cooled by contact with the solid carbon dioxide, and thereafter forcing the cooled paraffin solvent into the surrounding formation.

5. In a method of treating a well to remove 55 paraffin and the like, said well having liquid standing in the well bore, the steps which comprise removing the liquid from the well bore, introducing a cooling agent into the well bore, thereafter introducing a paraffin solvent into the well bore whereby the paraffin solvent is cooled by contact with the cooling agent and forcing it therefrom into the surrounding formation.

PAUL G. SHELLEY.
